UNITED STATES PATENT OFFICE

DENNIS J. SULLIVAN, OF LYNN, MASSACHUSETTS, ASSIGNOR TO UNITED SHOE MANUFACTURING CORPORATION, OF PATERSON, NEW JERSEY, A CORPORATION OF NEW JERSEY

ATTACHMENT OF TOP LIFTS TO WOOD HEELS

Application filed May 28, 1927. Serial No. 194,986.

This invention relates to improvements in the attachment of top lifts to wood heels and to improved wood heels.

In attempting to attach top lifts to wood heels by rows of slugs or other fastenings inserted through the top lifts parallel to and near the edges of the top lifts and heels difficulty has been experienced by reason of the tendency of the heels to split adjacent to their breast corners. The grain of the wood of wood heels runs lengthwise of the heels and when a row of fastenings is inserted parallel to the edge of the top lift and spaced $\frac{1}{16}$ of an inch or so from the edge of the top lift with the fastenings $\frac{3}{32}$ or $\frac{1}{8}$ of an inch apart the strain put upon the wood is often more than it can stand, particularly in the case of high heels having small top lifts. For this reason heretofore, in order to obviate the losses due to excessive splitting of heels, the more usual practice has been to rely upon fastenings inserted a considerable distance from the edge of the heel to hold the top lift in place, the slugs, if any there be, being driven into the top lift but not any substantial distance into the wood of the heel.

It is an object of the present invention to provide a method of attaching top lifts to wood heels which will eliminate the danger of splitting the heel even though a row of closely spaced fastenings be driven through the top lift into the wood heel close to the edge of the top lift and heel. I have discovered that if holes for the reception of the fastenings are made with an awl having a V-shaped or chisel point positioned with the edge of the point of the awl substantially normal to the edge of the heel, and thus extending transversely of the grain of the wood when operating near the heel breast corners, the danger of splitting the wood of the heel adjacent to the breast corners of the heel is practically eliminated. In the case of wood heels having leather top lifts, moreover, the passage of the chisel point of the awl through the leather top lift is effective to force the fibre of the leather of the top lift below the surface of the wood of the heel, depressions into which the fibre of the

leather is dragged being formed at opposite sides of the holes. This prevents the top lifts from working on the heel, and provides an unusually secure attachment for the top lift.

In another aspect this invention comprises a wood heel having a leather top lift attached thereto by fastenings, for example paper pegs, inserted through the top lift into the heel with the fibre of the leather adjacent to the fastenings forced downwardly below the surface of the wood of the heel, and thereby preventing the top lift from working upon the heel and eventually becoming loose.

With the above and other objects in view the invention will now be described with reference to the accompanying drawings and pointed out in the claims.

In the drawings,

Fig. 1 is a perspective view on an enlarged scale, partly broken away and partly in section, illustrating the attachment of a top lift to a wood heel in accordance with the present invention;

Fig. 2 is a front elevation of the operating instrumentalities of a fastening inserting machine which may be utilized in practicing the invention;

Fig. 3 is a side elevation on the same scale as Fig. 1 of an awl having a so-called chisel point which may be used in practicing the invention;

Fig. 4 is a vertical section taken on the line IV-IV of Fig. 1.

The wood heel of Fig. 1 is provided with the usual wooden body member 10 having a covering 12 of any suitable material, for example leather or celluloid, and a top lift 14 illustrated as of leather. In attaching the top lift to the heel in accordance with my invention, the heel with the top lift held in position, for example manually, may be placed upon the work support 16 of a fastening inserting machine of known type provided with a presser plate 18, a gage 20, a work penetrating and feeding awl 22, and a driver 24 reciprocating through a throat member 26 provided with a driver-passage 28. This machine (which, as illustrated, is of the well-

known type disclosed for example by Letters Patent of the United States No. 786,190, granted March 28, 1905, on an application of Louis A. Casgrain) may, in accordance with modern practice, advantageously insert paper pegs 30 into the openings formed in the work by the awl 22. In order to avoid splitting the wood of the heel adjacent to the heel breast corners, the awl 22 is provided with a V-shaped or chisel point 32 (Figs. 1 and 3) arranged with its edge substantially normal to the edge of the heel, as illustrated in Figs. 1 and 2, and thus extending transversely of the grain of the wood when operating in the vicinity of the breast corners of the heel. Thus the edge of the chisel point 32 of the awl will engage the top lift along such a line as is indicated at 34 in Fig. 1. The use of an awl having a chisel point of this character not only substantially eliminates the splitting of wood heels, but also serves to force the fibre of a leather top lift down below the surface of the wood of the heel at opposite sides of the fastening 30 as illustrated at 36 in Fig. 4. This action is accomplished by means of the inclined surfaces 38 and 40 on opposite sides of the chisel point 32 of the awl, and does not take place, at least to any substantial extent, as viewed upon planes defined by the axis and the edge of the chisel point of the awl. This forcing of the fibre of the leather top lift down below the surface of the wood of the heel makes a much more secure attachment than would otherwise be provided, locking the fastenings in the wood and preventing the top lift from working on the wheel when the shoe to which the heel is attached is worn.

Having thus described my invention, what I claim as new and desire to secure by Letters Patent of the United States is:

1. That improvement in methods of attaching top lifts to wood heels which comprises holding a top lift and a wood heel in assembled relation, making holes through the top lift into the wood of the heel with an awl having a chisel point positioned with its edge extending in a direction substantially normal to the edge of the heel, and inserting fastenings in the holes thus formed.

2. That improvement in methods of attaching top lifts to wood heels which comprises making holes through a leather top lift into a wood heel with an awl having a chisel point positioned with its edge substantially normal to the edge of the heel and thereby forcing the fibre of the leather of the top lift below the surface of the wood of the heel at opposite sides of the holes, and inserting fastenings in the holes thus formed.

3. That improvement in methods of attaching top lifts to wood heels which comprises making holes through a top lift into a heel with an awl having a point substantially V-shaped in cross-section positioned with its

edge substantially normal to the edge of the heel and thereby forcing the fibre of the leather of the top lift below the surface of the wood of the heel, and driving paper pegs in the holes thus formed.

4. That improvement in methods of attaching top lifts to wood heels which comprises making holes through a top lift into a wood heel adjacent to the breast corners of the heel with an awl having a chisel point, with the edge of the chisel point of the awl extending transversely of the grain of the wood of the heel, and inserting fastenings in the holes thus formed.

5. That improvement in methods of attaching leather top lifts to wood heels by paper pegs inserted through the top lifts into the heels characterized by forcing the fibre of the leather adjacent to the paper pegs downwardly below the surface of the wood of the heel at opposite sides of the pegs.

6. A wood heel having a leather top lift attached thereto by paper pegs inserted through the top lift into the heel, the fibre of the leather adjacent to the pegs being forced downwardly below the surface of the wood of the heel at opposite sides of the pegs.

In testimony whereof I have signed my name to this specification.
